UNITED STATES PATENT OFFICE.

JOHN F. MONNOT, OF PARIS, FRANCE.

ELECTRIC HEATER.

1,058,380.

Specification of Letters Patent.

Patented Apr. 8, 1913.

Application filed December 10, 1910. Serial No. 596,708.

To all whom it may concern:

Be it known that I, JOHN F. MONNOT, a citizen of the United States, and a resident of Paris, France, have invented a certain new and useful Electric Heater, of which the following is a specification.

My invention relates to electric heaters, and particularly to the heating elements thereof, and embodies an improved construction whereby the heating coils are protected against deteriorating influences, and whereby ineffective production of heat as radiant heat rather than as sensible heat, is substantially obviated.

When bare resistance coils are employed for heating air and the like, there is, in effect, much loss of heat, since much of the heat generated is generated as radiant heat, which passes through the surrounding air without raising the temperature of that air materially, and which, in effect, becomes sensible heat only when it impinges upon some solid or liquid body not transparent to heat rays. To obviate this loss, the coils must be embedded in some material, not transparent to heat, but merely conductive of heat, whereby all of the heat generated will be transmitted from the heater as sensible heat. In the past, this has generally been accomplished by embedding the coils in porcelain or like material; to which practice, however, there are numerous serious disadvantages, one of which is that the porcelain is extremely apt to break as a result of sudden temperature changes, or unequal heating, and another of which is that the porcelain does not allow free expansion and contraction of heating coils. A further objection is that porcelain is a rather poor conductor of heat and therefore is a poor radiating material and furthermore does not afford sufficiently large heating surface for contact with the surrounding air to heat the latter.

I have found that the best results are obtained by surrounding the heating coils with a finely pulverulent material of an insulating nature, inclosed within a sealed envelop, which latter is preferably of a material having a high rate of heat transmission, such as one of the more conductive metals. The pulverulent material then performs the several functions of insulating the heating coils electrically from one another, of excluding air from the coils and there-

by preventing oxidation, of converting all radiant heat admitted from the coils into sensible heat, of storing heat so that the rise and fall of temperature of the resistance coils is relatively gradual, of cushioning the structure so that it is not liable to injury even by excessive jar or vibration, and of permitting free expansion and contraction of the coils.

I am aware that it has heretofore been proposed to surround electric heating coils with white sand (quartz sand) for the accomplishment of some of the functions above mentioned; but such heaters have been in effect inoperative, at least for more than very moderate temperatures, since quartz and quartz sand and like substances, though good insulators at ordinary atmospheric temperatures, become quite conductive of electricity at temperatures of and above 300° centigrade; the effect of the use of quartz sand therefore is to short circuit the heating coils, reducing their resistances greatly, and therefore substantially destroying the heating value of the apparatus and making it extremely wasteful of current. I have discovered, however, that there are substances, capable of existing in the pulverulent form, at temperatures of and above 300° centigrade, which are still good insulators at and above such temperature. One such substance is plaster of Paris (calcium sulfate); another is slate; these materials and other materials which also have the property of remaining substantially non-conductive, at temperatures such as 300° centigrade and over, may therefore be used successfully to surround the heating coils of an electric resistance heater. In the construction of my heating element therefore, I use as a filling, some material which is substantially non-conductive, not only at atmospheric temperatures, but also at temperatures of and over 300° centigrade, and which will remain in pulverulent condition throughout this temperature range.

In the accompanying drawing I illustrate more or less diagrammatically one form of heater embodying my invention, the said drawing showing a central longitudinal section of heating element.

In said drawing 1 designates a hollow support of non-conducting material—preferably material of a refractory nature; I have found ordinary earthenware suitable for

the purpose. Upon this support is wound a resistance wire 2, of which 3 and 4 are the terminal conductors, while 5 is a conductor leading to an intermediate point of the resistance coil. These three conductors preferably pass through the center of the support 1, to and through the end cap herein-after mentioned, and it will be obvious that, by suitable switching means, whereby conductors 3 and 4, or 3 and 5, or 4 and 5, or 3, 4 and 5, are placed in circuit, various combinations of resistance may be obtained, and therefore various heating effects may be realized, and the degree of heat generated may be regulated.

6 designates an envelop, preferably a metallic envelop, surrounding the support 1 and between which envelop and support there is a space preferably as narrow as is consistent with the cushioning action of the filling material, filled with pulverulent insulating material 7 of the character above mentioned; that is, a material which is a non-conductor from ordinary atmospheric temperatures to temperatures of 300° centigrade and over, and which remains pulverulent throughout this temperature range. The interior of the support 1 is preferably filled with the same material. This envelop is closed at the bottom by a head 8 and at the top by sealing material 9. Customarily also I provide a further top covering 10.

In constructing this heating element, the various parts are well dried, preferably before assembling, and when the support 1 with the resistance coil thereon has been placed within the envelop, and the pulverulent material has been placed within the space between the envelop and support 1 and also within the support 1, a considerable electric current is passed through the resistance coil to heat the parts, both for the purpose of driving out any remaining moisture and of driving out so much of the contained air as possible. The envelop is then tightly sealed, the conductors 3, 4 and 5 being embedded in the sealing material 9, which is preferably a sealing material which is liquid or plastic at some high temperature much above any temperature which the parts of the heating element will reach in practice, and the top cap is applied. It will be noted that owing to the entire interior of the envelop being practically filled with the pulverulent material, the only air which the envelop contains, after sealing, is the slight amount of attenuated air remaining imprisoned between the particles of the pulverulent material and clinging to the sides of the parts; this amount being extremely small. The oxygen of the air so imprisoned will speedily unite with the metal of the heating coil, if that metal be one which is readily oxidized, but the amount of oxygen contained within the heating element, is at

most so small that no harmful oxidation of the resistance coil can result from it.

It is well known that resistance coils formed of many metals, German silver for instance, become very fragile, after repeated use under ordinary conditions. I have discovered that such fragility is not due to oxidation as has been supposed, but is due to changes resulting from too rapid heating and cooling of the metal. The pulverulent material 7 of my heating element, and the support 1 for the resistance coil have, collectively, a relatively large heat-storing capacity, which, enforces slow heating up and slow cooling of the resistance coil, the effect on the metal of which is equivalent to that of slow annealing; so that I have found that heating coils so protected and surrounded are not subject to the deterioration previously mentioned, but to the contrary, the metal retains its ductility after long use. The pulverulent material 7 is capable of yielding sufficiently to permit substantially free expansion and contraction of the heating coils, and to cushion the parts so that mechanical injury is obviated. Such filling material also intercepts the rays of radiant energy emitted from the heating coils, converting same into sensible heat and conducting such heat to the envelop, from which it is radiated to the outer air or other medium surrounding said heating envelop.

To insure efficient transmission of heat from the resistance conductor through the pulverulent filling material and the metallic envelop to the outside air or other surrounding medium, it is important that the space between the resistance conductor and the metallic envelop, that is to say, the space occupied by the pulverulent filling material, shall be as small as is consistent with the described cushioning action of the pulverulent material. It is also extremely important that the filling material be as non-conductive of electricity as possible; hence the choice of a material which remains a substantial non-conductor at temperatures of or even above 300° centigrade, also the use of the sealing material 9 which hermetically seals the contents of the metallic envelop, absolutely preventing entrance of air, and, in so doing, absolutely preventing the entrance of moisture which, if it entered, would impair the insulation and lead to short-circuiting.

For the pulverulent filling material I preferably employ plaster of Paris, as this material is cheap, is very finely pulverulent, does not become plastic or molten if at high temperature, and is a good insulating material even at high temperature.

It will be obvious that this heating element may be made in various forms and sizes and of various constructions,

What I claim is:—

1. An electric heating element comprising an envelop having hermetically sealed within it an electric resistance conductor 5 embedded in a pulverulent mass of material which is substantially non-conductive of electricity from ordinary atmospheric temperatures to 300° centigrade. 20
2. An electric heating element comprising an envelop having hermetically sealed within it an electric resistance conductor 10 embedded in a mass of pulverulent plaster of Paris.
3. An electric heating element comprising 15 an envelop having within it a refractory
- support and an electric resistance conductor mounted upon said support, the space between said support and walls of the envelop being filled with a pulverulent mass of material which is substantially non-conductive of electricity from ordinary atmospheric temperatures to 300° centigrade, said envelop provided with means hermetically sealing its contents within it. 25

In testimony whereof I affix my signature, in the presence of two witnesses.
